UNITED STATES PATENT OFFICE.

ARTHUR L. PASCHALL, OF SAN SIMON, ARIZONA.

DENTAL-FLOSS HOLDER.

1,214,362.

Specification of Letters Patent. Patented Jan. 30, 1917.

Application filed August 26, 1913, Serial No. 786,753. Renewed November 15, 1916. Serial No. 131,570.

To all whom it may concern:

Be it known that I, ARTHUR L. PASCHALL, a citizen of the United States, residing at San Simon, in the county of Cochise and 5 State of Arizona, have invented new and useful Improvements in Dental-Floss Holders, of which the following is a specification.

The invention relates generally to tooth 10 cleaning devices, and particularly to a holder adapted to contain a spool of dental floss, the holder being constructed to permit the positioning of the proper length of such floss on the holder to permit necessary tooth 15 cleaning operation.

The main object of the present invention is the provision of a dental floss holder in which the floss, wound upon a spool is normally housed within a protecting casing 20 forming part of the holder, the holder further including a means for guiding the terminal strand from the spool and for securing a portion thereof in comparatively taut condition and in a position for convenient 25 application and use for tooth cleaning purposes.

The invention in its preferred form of details will be described in the following specification, reference being had particularly to the accompanying drawings, in 30 which:—

Figure 1 is a broken plan of the device. Fig. 2 is a longitudinal sectional view of the same. Fig. 3 is a broken elevation of 35 one of the arms.

In Figs. 1, 2, and 3 I have shown a form of structure wherein 27 represents a hollow shank formed at one end to provide divergent arms 28 and 29 supporting the operative 40 length of the thread. The shank is hollow throughout the length and gradually convergent from the end remote from the arms 28 and 29 toward said arms, whereby when the thread is drawn from the spool as 45 hereinafter described said thread is prevented from meeting an angular edge. In this instance the arm 29 is hollow throughout its length to permit a complete un-

broken housing for the full length of the thread except that portion actually in use. 50 The arm 29 is provided with a guide 30, while the arm 28 is terminally provided with a guide 31. The end of the shank remote from the arms is extended in the form of spaced semi-circular plates 32 forming in 55 effect one half of the housing, the remaining housing section 33 being similarly formed and being hinged to the section 32 at one end, a catch 34 securing the parts in connected relation. The longitudinal centers of the free edges of the housing section 32 are formed with offset projections 35 forming recesses for the reception of the terminals of the spool spindle 36, the spool 60 37 being preferably integral with the spindle and adapted to support the desired quantity of thread wound thereon. The section 33 of the casing is formed at appropriate points with offsets 38 to overlie and reinforce the offsets 35 when the sections are 65 70 in casing forming relation.

In the form described, it will be obvious that means are provided for conveniently adjusting a new length of the thread in the holder for use, the remaining portions of 75 the thread being, at least in certain of the forms, fully housed and protected against outside influence. In every instance, the spool may be readily replaced when exhausted. 80

The holder is complete, providing a simple article which aside from the details of construction described, may be ornamental to any desired extent and may be constructed of any appropriate material. 85

What is claimed is:—

In a device of the class described, in combination a hollow shank, divergent arms formed integrally upon said shank, one of said arms being formed hollow so as to communicate with said hollow shank, thread guides carried by said arms at their outer ends, said shank being provided with spaced semicircular plates forming one-half of a housing, a semicircular housing 90 section hingedly connected to said plates, a 95

catch adapted to secure the said sections of the housing together, said first-named housing section being formed with off set projections forming pintle bearings, a spool having integral oppositely extending pintles arranged to seat in said bearings and to snap out of the same to remove the spool, the other housing section being formed with off-

sets adapted to overlie and reinforce said first named offsets.

In testimony whereof I affix my signature in presence of two witnesses.

ARTHUR L. PASCHALL.
